CLAIM

The ornamental design for package for cosmetic products, as shown and described.

DESCRIPTION

FIG. 1 is a perspective view of a package for cosmetic products, in an open condition, showing my new design;

FIG. 2 is a perspective view thereof, with the compartments shown in an alternate position from that shown in FIG. 1;

FIG. 3 is a top plan view thereof;

FIG. 4 is a bottom plan view;

FIG. 5 is a front elevation view;

FIG. 6 is a side elevation view, the opposite side being substantially a mirror image; and

FIG. 7 is a rear elevation view.

FIG. 8 is a cross-sectional view taken on the line 8—8 of FIG. 3.
